US00D970450S

(12) United States Design Patent (10) Patent No.: US D970,450 S
(45) Date of Patent: * Nov. 22, 2022

(54) FURNITURE POWER DISTRIBUTION UNIT

(71) Applicant: Changzhou Cheng Ling Electronics Co., Ltd, Changzhou (CN)

(72) Inventor: Chenglin Wang, Changzhou (CN)

() Term: 15 Years

(21) Appl. No.: 29/822,245

(22) Filed: Jan. 7, 2022

(51) LOC (13) Cl. 13-03

(52) U.S. Cl.

USPC D13/137.4

(58) Field of Classification Search

USPC D13/107, 108, 110, 137.1, 137.2, 137.3, D13/137.4, 138.1, 138.2, 139.1, 139.2, D13/139.3, 139.4, 139.5, 139.6, 139.7, D13/139.8, 146, 151, 152, 153, 154, 158, D13/159, 160, 161, 162, 162.1, 163, 164, D13/165, 166, 167, 168, 169, 171, 172, D13/173, 174, 175, 176, 177, 178, 179, D13/184, 199

(57) CLAIM

The ornamental design for a furniture power distribution unit, as shown and described.

DESCRIPTION

FIG. 1 is a perspective view of a furniture power distribution unit showing my new design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged detail view of the encircled area 9, shown in FIG. 1; and,

FIG. 10 is another enlarged detail view of the encircled area 10, shown in FIG. 1.

The broken lines encircling the detail portions in FIG. 1 illustrate the boundaries of the detail portions, and form no part of the claimed design.

1 Claim, 9 Drawing Sheets
